US00D533392S

(12) United States Design Patent (10) Patent No.: US D533,392 S
(45) Date of Patent: * Dec. 12, 2006

(54) SANDWICH MAKER

(75) Inventor: Kui Wong Yeung, Hong Kong (HK)

(73) Assignee: Homemax (Hong Kong) Limited,
Hong Kong (HK)

() Term: 14 Years

(21) Appl. No.: 29/244,269

(22) Filed: Dec. 7, 2005

(30) Foreign Application Priority Data

Jun. 8, 2005 (HK) 0501363

(51) LOC (8) Cl. 07-02

(52) U.S. Cl. D7/352

(58) Field of Classification Search D7/323,
D7/328-332, 334-339, 352-363; 99/219,
99/331, 339, 349, 369, 372-375, 385, 386,
99/389, 425, 444, 446, 466, 601, 618, 620;
219/524, 525, 620-622, 732-734; D21/525

See application file for complete search history.
